UNITED STATES PATENT OFFICE.

HUGO MAUL AND FREDERICK LANDENBERGER, OF NEW YORK, N. Y.

DESIGN FOR CHENILLE.

SPECIFICATION forming part of Design No. 16,366, dated November 3, 1885.

Application filed July 23, 1883. Serial No. 172,471. Term of patent 7 years.

To all whom it may concern:

Be it known that we, HUGO MAUL and FREDERICK LANDENBERGER, both of the city, county, and State of New York, have invented 5 and produced a new and original Design for Chenille, of which the following is a full, clear, and exact description.

The leading features of our design consist of depressions in the chenille which are slightly 10 spiral or diagonal to the center line of the chenille, and are deeper at one part or side of the chenille than at the other; and, second- 15 ly, of depressions in the chenille which are slightly spiral or diagonal to the center line of the chenille and deeper at one part or side of the chenille than at the other, forming slightly-elliptical rings that inclose flat sur- 20 faces.

Reference is to be had to the accompanying 25 drawings, forming part of this specification, in which similar letters of reference indicate corresponding parts in both the figures.

Figure 1 is a plan view of our newly-designed chenille, and Fig. 2 is a sectional elevation of 30 the same.

a a are annular depressions on the chenille. Between the depressions *a a* the chenille is of full diameter, showing the large tufted rings or bands *b b*, and in the depressions *a a* are 35 the small curved differently-appearing sur-

faces *c*. The surfaces *c* are flat and slightly spiral, and are slightly diagonal to the longitudinal center of the chenille. The depressions *a* are also slightly spiral or diagonal to the center line of the chenille, and are deeper 35 at one part or side of the chenille than at the other, forming the slightly-elliptical rings *a'* around the chenille, that inclose the flat surfaces *c*, so that the chenille presents to the eye an auger-like but slightly-irregular appear- 40 ance.

We claim—

1. The design for chenille herein shown and described, the same consisting of the depressions in the chenille, which are slightly spiral or diagonal to the center line of the chenille, and are deeper at one part or side of the chenille than at the other. 45

2. The design for chenille herein shown and described, the same consisting of the depressions in the chenille, which are slightly spiral or diagonal to the center line of the chenille, and are deeper at one part or side of the chenille than at the other, forming slightly-elliptical rings that inclose flat surfaces. 50

HUGO MAUL.

FREDERICK LANDENBERGER.
